US00D998160S

(12) United States Design Patent (10) Patent No.: US D998,160 S
(45) Date of Patent: * Sep. 5, 2023

(54) BODY SCULPTING MACHINE

(71) Applicants: Jianhai Shao, Wenzhou (CN); Yuntian Qiu, Shenzhen (CN)

(72) Inventor: Jianhai Shao, Wenzhou (CN)

() Term: 15 Years

(21) Appl. No.: 29/889,706

(22) Filed: Apr. 15, 2023

(30) Foreign Application Priority Data

Oct. 17, 2022 (CN) 202230683359.9

(57) CLAIM

The ornamental design for a body sculpting machine, as shown and described.

DESCRIPTION

FIG. 1 is front, left and top perspective view of a body sculpting machine showing my new design;

FIG. 2 is a rear, right and bottom perspective view thereof;

FIG. 3 is a left view thereof;

FIG. 4 is a right view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines illustrate portions of the article that form no part of the claim.

1 Claim, 8 Drawing Sheets
